UNITED STATES PATENT OFFICE.

WILLIAM H. STUBBLEBINE, OF ALLENTOWN, PENNSYLVANIA.

RECUPERATOR-FURNACE.

1,279,932.

Specification of Letters Patent. Patented Sept. 24, 1918.

Application filed October 19, 1917. Serial No. 197,473.

To all whom it may concern:

Be it known that WILLIAM H. STUBBLEBINE, a citizen of the United States, residing at Allentown, in the county of Lehigh and State of Penna., has invented certain new and useful Improvements in Recuperator-Furnaces; and he does hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in recuperator furnace, and consists of a simple and efficient apparatus of this nature which may be installed upon various types of metallurgical furnaces, having various details of construction, combinations and arrangements of parts which will be hereinafter fully described, shown in the accompanying drawings and then specifically defined in the appended claim.

I illustrate my invention in the accompanying drawings, which with the letters of reference marked thereon, form a part of this specification and in which:

30 Figure 1 is a central vertical sectional view through the recuperator.

Fig. 2 is a longitudinal sectional view taken on line 2—2 of Fig. 1.

Fig. 3 is a sectional view through the recuperator taken on line 3—3 of Fig. 1.

Fig. 4 is a vertical sectional view on line 4—4 of Fig. 1, and

Fig. 5 is a sectional view on line 5—5 of Fig. 1, a portion of the recuperator being shown in elevation.

Reference now being had to the details of the drawings by numerals:

1 designates the fire box of the recuperator in which the grate 2 is mounted, and 3 designates the working chamber in which the charge of iron or steel to be melted or pre-heated is placed and in which chamber it is necessary to maintain an intense heat. The furnace is provided with a fuel opening 4 in which coal may be introduced, and openings 5 are formed in the front wall of the furnace, through which pipes 6 pass and affording means through which pulverized fuel may be fed into the furnace when desired. A pipe 7 passes through the side wall of the furnace below the grate and through

which pipe a blast of air may be introduced into the furnace. Another pipe 8 is provided with branches 9 leading through openings in the front wall of the pre-heating chamber 10 and communicates with the coils 11, and which latter have nozzles 12 opening into the chamber 10 and through which coils air is introduced. The top wall of the chamber is provided with flues 13, which communicate with the passageway 14, which in turn communicates with the chamber 10. Flues 15 are formed in the front wall of the furnace, affording means for communication between the same and the chamber 10 near the forward lower portion thereof, as shown in Fig. 1 of the drawings.

The combustion of fuel within the fire chamber will be expedited by the blast of air introduced through the pipe 7 and the greater part of the gas in the fire chamber will pass over the bridge wall 16 into the working chamber 3. A separate blast will be supplied to the passageway 14 through the pipes 9 and coils in which it is pre-heated. The blast of air passing from the coils through the nozzles 12 into the chamber 10 will create a suction which will draw a certain percentage of the gas into the pre-heating chamber 10 through the ports 15 and 16 which will heat the air therein about the coils 11, thus further preheating the air which passes through the said coils and before it makes exit into the chamber 10. As the air emerges from the nozzles 12 and 17 commingles with the gases in the chamber 10, the gas and air will be mixed in the latter and the passageway 14 and will make exit through the ports 13 into the working chamber 3. After the furnace is in operation, the coils 11 in the chamber 10 will become thoroughly heated by the gases in said chamber and in turn will pre-heat the air passing through the coils. The admission of this mixture of pre-heated air and gas through the ports 13 into the working chamber will produce a very high degree of heat, thus enabling the operator to obtain a much increased production over that which would be possible to obtain by the ordinary types of furnace. In addition to the main recuperation described, there is an auxiliary recuperation adjacent to the flues of the furnace and through the medium of the pipe 18 having branches 19 leading through the rear wall 20 and which communicate with the coils 21 located in the chamber 22. The

wall 20 of the furnace is provided with flues 23 communicating between the working chamber and the chamber 22. The blast of air entering through the pipe 18 into the 5 coils 21 becomes heated before emerging from the nozzles 24 into the flues 25. Said flues 25 communicate between the chamber 21 and the working chamber through the medium of the ports 26 in the side wall of 10 the latter.

The operation of the auxiliary recuperator is similar to that of the main recuperator, with the exception that the suction created by the blast of air passing through the 15 nozzles 24 will draw a certain percentage of the gas through the working chamber through the ports 23. The air emerging from the nozzles 24 commingles with the gases coming from the chamber 22 and 20 mixes in the flues 25 and makes exit into the working chamber 3 through the ports 26. With the use of the auxiliary recuperator, the operator may have perfect control 25 of the heat in the furnace.

What I claim to be new is:—

A recuperator furnace having a grate therein, and a working chamber, a pre-heat-

ing chamber with flues communicating between the same and the fire chamber, a passageway leading from the pre-heating chamber and communicating with the fire chamber through flues in the roof thereof, coils mounted within said pre-heating chamber and having connection with an air supply pipe, nozzles connected to said coils and 30 opening into the pre-heating chamber, and a blast pipe communicating with the fire chamber, an auxiliary recuperating chamber having ports communicating between the same and the working chamber, the walls of 35 the latter provided with passageways having ports leading therefrom into the working chamber, air-heating coils positioned within said auxiliary recuperating chamber, and having nozzles leading therefrom into 40 said passageways in the walls of the working chamber.

In testimony whereof I hereunto affix my signature in presence of two witnesses.

WILLIAM H. STUBBLEBINE.
